UNITED STATES PATENT OFFICE

FRED W. WARNER, OF DENVER, COLORADO, ASSIGNOR OF ONE-HALF TO EVA A. WARNER

TOY CALL BOX

Original application filed October 8, 1925, Serial No. 61,238. Patent No. 1,693,128, dated November 27, 1928. Divided and this application filed November 19, 1928. Serial No. 320,290.

This invention relates to toys and its primary object is to provide a miniature call box of the type found at street corners of towns and cities to signal the occurrence of a fire or other calamity to a fire or police station.

Another object is to provide a toy call box equipped with mechanism for the operation of a distant movable element such as the doors of a toy fire-house.

Another object is to provide a toy call box of the above stated character in combination with an element capable of being moved by the operation thereof.

15 A further object is to provide in association with a toy call box, a gong or other alarm actuated by its operating mechanism, and still other objects reside in details of construction, as shown in the accompanying drawings.

The present application is divisional of my Patent No. 1,693,128, issued the 27th day of November, 1928.

In the drawings in the several views of 25 which like parts have been similarly designated,

Figure 1 represents a perspective view of the toy call box in association with a toy fire house, a wall and the roof of the latter 30 having been partially broken, to disclose the interior of the house,

Figure 2 is a fragmentary sectional elevation of the toy call box,

Figure 3, a front view of the upper portion of the same, looking in the direction of the arrow A in Figure 2, and

Figure 4, an enlarged fragmentary section on the line 4—4, Figure 3, showing the construction of the alarm-sounding element of 40 the box.

The call box as shown, comprises a box 5 supported on a pedestal 6. The box has a door 7 closing the front thereof and the pedestal has a weighted base or foot 8 for 45 its support on a floor or table. The door has a latch 9 to lock it in its closed position.

The stem 10 of the pedestal may be made of a piece of tubing inserted in a socket of the base. This socket is preferably provided by an angular passage, the upright

branch 12 of which opens in the center of the base at the top thereof and the horizontal branch 13 of which extends along the undersurface of the base and opens at a side thereof.

55 A small pulley 14 is rotatably mounted at the point of intersection of the two branches of the passage, for the guidance of a pull cord 15 that extends through the tubular stem into the box.

60 Mounted inside the box by means of a horizontal spindle 16 is a pulley 17 that supports the upper portion of the cord 15 which at its end is provided with a handle 18 to facilitate its manipulation.

65 At a side of the box is a gong 19 and a clapper 20 fulcrumed at 21, is engaged by a projecting trip 22 on the shaft 16 of the pulley 17 to engage the gong when the pulley is rotated by means of the pull cord.

70 The end of the portion of the pull cord extending from the base of the pedestal, is connected with some movable device such as the latch bar 23 of the spring-pressed doors 24 of a toy fire house 25, shown in the drawings.

75 When this bar is pulled outwardly, the doors are released, thereby permitting the exit of a spring-actuated toy fire engine 26 that stands against the doors inside the fire house when the doors are closed. The clapper-movement of a gong 27 at a side of the fire house is connected with the pull cord 15 by a cord 28.

80 In using the toy, the alarm box is placed at a distance from the actuated element, the distance being determined by the length of the pull cord.

85 When a fire station such as shown in the drawings, is used in connection with the call box, the two elements may be placed in connecting rooms or at opposite ends of a long passage so that two children may take active parts in the operation, one of them, for example, acting as a policeman who, upon discovery of the fire, "pulls" the call box, while the other takes the part of the captain of the fire company who superintends the departure of the fire engine from the station.

The child at the call box, opens the door and moves the cord 15 by a downward pull on the handle 18. The movement of the cord opens the doors of the fire house and sounds the gong 27, as hereinbefore explained, and the rotation of the shaft of the pulley 17 in the call box, sounds the gong 19 by actuation of its clapper through the instrumentality of the trip on the shaft.

What I claim and desire to secure by Letters Patent is:

1. A toy call-box for the operation of a toy fire-house at a distant point, comprising a portable stand having a foot for its loose support in an operative condition on a surface, an element adapted for the operation of an actuated part of the toy fire-house, means on the stand for the operative support of the element, and an alarm operatively associated with said means.
2. A toy call-box for the operation of a toy fire-house at a distant point, comprising a portable stand having a foot for its loose support in an operative condition on a surface, an element for the operation of an actuated part of the toy fire-house, including means for its connection with said part, means on the stand for the operative support of the element, and an alarm operatively associated with the element.
3. A toy call-box for the operation of a toy fire-house at a distant point, comprising a portable stand having a foot for its loose support in an operative condition on a surface, and a pull-cord operatively supported by the stand, and means on the pull-cord for its connection with an actuated part of the toy fire-house.
4. A toy call-box for the operation of a toy fire-house at a distant point, comprising a portable stand having a foot for its loose support in an operative condition on a surface, a pulley at the foot of the stand, a second pulley on the stand above the other, a pull cord supported by the pulleys for lengthwise motion, and having means for its connection with an actuated part of the fire-house, an alarm on the stand, and means associated with one of the pulleys for sounding the alarm by movement thereof.
5. A toy call-box for the operation of a toy fire-house at a distant point, comprising a portable stand having a foot for its loose support in an operative condition on a surface, and including a pedestal and a door-closed box on the pedestal, a pull-cord having means for its connection with an actuated part of the fire-house, means in the box for the operation of the pull-cord, and a pulley at the foot of the pedestal to guide the pull-cord in a lengthwise movement.
6. A toy call-box for the operation of a toy fire-house at a distant point, comprising a portable stand having a foot for its loose support in an operative condition on a sur-

face, and including a hollow pedestal and a door-closed box on the pedestal, a pull cord having means for its connection with an actuated part of the fire-house, and extending through the pedestal into the box, means in the box for the operation of the pull cord, and a pulley at the foot of the pedestal to guide the pull cord in a lengthwise movement.

In testimony whereof I have affixed my signature.

FRED W. WARNER.
